UNITED STATES PATENT OFFICE.

POWELL EVANS, OF PHILADELPHIA, PENNSYLVANIA, ASSIGNOR, BY MESNE ASSIGNMENTS, TO GLOBE AUTOMATIC SPRINKLER COMPANY, OF PHILADELPHIA, PENNSYLVANIA, A CORPORATION OF PENNSYLVANIA.

FLOW-RETARDING APPARATUS.

1,267,857.

Specification of Letters Patent.

Patented May 28, 1918.

Application filed December 17, 1914. Serial No. 877,786.

To all whom it may concern:

Be it known that I, POWELL EVANS, a citizen of the United States, residing in Philadelphia, Pennsylvania, have invented certain Improvements in Flow-Retarding Apparatus, of which the following is a specification.

One object of my invention is to provide a relatively simple, substantial and reliable device for causing a predetermined delay or retardation in any flow of water between the dry portion of a sprinkler system and alarm apparatus, regardless of the pressure of said water; the arrangement of parts being such as will cause their positive operation and the flow of water to said alarm apparatus only after it has flowed to said device for a predetermined time and a predetermined rate.

20 These objects and other advantageous ends I secure as hereinafter set forth, reference being had to the accompanying drawings, in which,

Figure 1 is a vertical section of a flow 25 retarding device constructed according to my invention; this figure also showing in section the apparatus ordinarily associated with said device;

Fig. 2 is a vertical section on larger scale 30 than Fig. 1, further illustrating the construction of the invention;

Fig. 3 is a horizontal section on the line a—a, Fig. 2; and

Fig. 4 is a fragmentary vertical section 35 illustrating a slightly modified form of a part of the device.

In the above drawings 1 represents a receiving chamber in the form of a domelike casing open at its bottom and having connected to it in any suitable manner, as by bolts, a ring 2. Between this latter and the flanged mouth of the chamber 1 is confined a diaphragm 3 and a second diaphragm 4 is likewise mounted between the 45 lower face of said ring 2 and a hollow cap 5.

Adjacent the bottom of the chamber 1 is a conduit 6 opening at the side thereof where it is threaded for the reception of 50 a bushing 7 to which is connected a pipe 8 leading from the auxiliary valve 37 of an alarm valve 31 connected in the water supply pipe 32 of a sprinkler system. Between

the bushing 7 and the opposite wall of the conduit 6 is confined a cylindrical screen 9 which is so mounted that its interior is in communication with the pipe 8, while the liquid passing through it will enter the conduit 6. This latter which is preferably integral with the casing structure, has a second outlet opening communicating with a passage 10 formed in a valve seat 11 suitably mounted in said structure.

The under face of said valve seat preferably has a concave curvature designed to receive the convexly curved surface of a valve 12 carried upon and in the present case forming part of a spindle 13 which passes centrally through both of the diaphragms 3 and 4. Between said diaphragms there is mounted upon the spindle a collar 14 having a flange at its upper end confining the diaphragm 3 against the under side of the valve 12, and at its opposite end has a second flange against which the diaphragm 4 is confined by a washer 15 held in place on the spindle 13 by a nut 16.

The diaphragm 3 at any suitable point has a small hole 17 through which liquid is free to pass from the interior of the chamber 1 into the space 18 between the two diaphragms or as shown in Fig. 4, the diaphragm 3^a is imperforate and an opening 17^a is provided into the passage 25 from whence small flows of water may pass to waste without operating the alarm devices. From this space a pipe 19 leads to a drain, while the space 20 formed below the diaphragm 4 by a hollow in the cover 5 is connected through a pipe 21 with that portion 90 of the alarm valve directly communicating with the water supply system, so that this space is normally full of liquid forcing upwardly the diaphragm 4 and with it pressing the valve 12 against its seat. Obviously 95 it may be connected to some other suitable part of the sprinkler system without departing from my invention. Said valve has a passage 22 of relatively small cross section whose ends open respectively at the center of its top and at one side below its curved part, so there is at all times a free opening from the conduit 8 through the passages 6 and 10 to the passage 22 of the valve and hence to the interior space 23 105 of the chamber 1. The seat 11, in addition

to the passage 10, is provided with an annular recess or passage 24 opening into a passage 25 formed in a suitable portion of the chamber casting 1 and this passage or recess is connected through any suitable number of passages 26 with the interior of said chamber, it being noted that they open on the face of the valve seat so as to be normally closed by the valve 12. The pipe 10 27 leads from this space or passage 25 to any suitable form of water actuated alarm device; in the present case to an alarm controlling device 33 and also to a water motor 31 designed to operate a gong 35.

15 Under conditions of operation the valve 12 is kept seated by the pressure of water in the chamber 20 delivered from the source of supply for the sprinkler system acting on the diaphragm 4 and it is noted that the 20 area of this diaphragm exposed to such pressure is materially less than the area of the exposed upper face of the diaphragm 3. The pipe 8 like the pipe 21 is connected to the alarm valve 31, but its inlet is normally 25 maintained closed by the valve 36. If for any reason the main clapper 36 of the alarm valve with the auxiliary valve 37 should momentarily open so as to allow of a temporary flow of water through the pipe 8, said 30 water passes through the screen 9 and passages 6, 10 and 22 into the space 23 within the chamber 1 and at once begins to leak into the space 18 between the diaphragms through the small opening 17, from whence it 35 passes through the pipe 19 to the drain or if the opening into the passage 25 is employed it passes into the pipe 27 and thence to the drain since its pressure and quantity are insufficient to actuate the alarm devices 33 and 34.

40 If after this opening, the alarm valve immediately closes, there is obviously no large amount of water collected within the space 23 and consequently no pressure on the diaphragm other than that due to the weight of 45 such water. The latter thus gradually passes out of the chamber 1 without affecting the alarm apparatus connected to the pipe 27.

If however, the main and auxiliary valves 36 and 37 remain open, as they would upon 50 operation of the sprinkler system, there would be a continued flow of water through the pipe 8, the passages 10 and 22, and into the cavity 23 of the chamber 1 around the valve 12. This would shortly be filled in 55 spite of the leakage through the openings 17 or 17^a, and a downward pressure would be exerted upon the diaphragm 3 due to the pressure of the water in the sprinkler system. Owing to the difference in the exposed 60 areas of the diaphragms 3 and 4, both of these latter would then be moved down against the pressure of the liquid in the space 50 and as soon as such downward movement has progressed far enough to expose the face of the valve 12, the force ex-

erted to move said diaphragms would be materially augmented owing to the increased area of the valve exposed to pressure.

Water is now free to flow from the cavity 23 of the chamber 1 through the passages 26 70 to the passage 24, cavity 25, and through the pipe 27 to the water actuated alarm apparatus 33 and 34, which is thus put in operation and continues to operate as long as water under pressure is delivered through 75 the pipe 8.

When the flow in the sprinkler system is cut off and the alarm valve again set in its closed position, the flow through the pipe 8 ceases and the liquid within the cavity 23 of 80 the chamber 1, as well as that in the associated passages flows out through the hole 17 to the drain 19, so that when liquid under pressure is again admitted to the alarm valve, it flows through the pipe 21 to the cavity 20 of the cover or cap 5, thereby again moving upwardly the two diaphragms and the valve 12. The latter then engages the concave face of its seat 11, cutting off the opening 26 from communication with the cavity 23 which, however, is still in communication with the pipe 8 through the passage 22 of the valve.

By the use of the above device the chattering of the alarm valve 36 on its seat due to 95 water hammer for example, such as would cause temporary opening, or the leakage of any water through the auxiliary valve 37 would be effectually prevented from causing operation of the alarm apparatus connected 100 to the pipe 27, since as previously noted, the water thus delivered to the cavity 23 of the casing would escape to the drain before it could accumulate above the diaphragm 3 in such quantities as would cause unseating 105 of the valve 12. When, however, the alarm valve 36 with the auxiliary valve 37 is opened by flow of water into the sprinkler system, the alarm apparatus is quickly put into operation, since the passages 26 are 110 fully uncovered by reason of the movement of the diaphragm due to the differential areas exposed to pressure and also because of the additional area exposed to the action of liquid in the cavity 23 by the unseating 115 of the valve 12, which causes its action to be certain and positive. It is to be noted that the outlet of the passage 10 is materially larger than the cross section of the passage 22, so that the unseating of the valve permits an increased inflow of water and causes the operation of the alarm apparatus 33 and 34 connected to the pipe 27 in a minimum of 120 time.

It will be noted that the flanged collar 14 125 and the washer 15 rigidly engage a relatively large area at the center of the diaphragm 4 and in addition I preferably provide a support such as the ring 30 for supporting that part of the diaphragm between 130

said collar and the structure 2 when the valve is seated, in order to prevent its abnormal deflection under the continued action of the water pressure in the chamber 20.

5. I claim:—

1. The combination in a flow retarding device of a casing having an inlet and an outlet; a diaphragm structure dividing said casing into chambers; a valve connected to

10 said structure and normally closing the outlet, there being an opening in the valve through which one of the chambers is open to the inlet; and means for supplying fluid under pressure to the other of the chambers

15 to hold the valve closed.

2. The combination in a flow retarding device of a casing having an inlet and an outlet; a diaphragm movably mounted in the casing; a valve carried by the dia-

20 phragm and normally closing the outlet while leaving the inlet partially open; there being a normally open waste outlet from the casing; and means for supplying fluid under pressure to hold the diaphragm in position to close the valve.

3. The combination in a flow retarding device of a casing; a valve seat therein; said casing having an inlet and an outlet both opening on said seat; a valve for the seat 30 formed to close the outlet and partly close the inlet; a diaphragm exposed to liquid under pressure in the casing; and means for normally holding the valve closed.

4. The combination of a casing having an 35 inlet; two diaphragms mounted to divide the casing into three chambers; means for connecting said chambers to the water supply of a sprinkler system; a conduit for connecting one of the chambers to an alarm 40 mechanism; with a valve normally closing said conduit and also restricting the inlet.

5. The combination in a flow retarding device of a casing having an inlet and an outlet; a valve normally closing the outlet 45 and restricting the inlet; the casing having also a normally open waste outlet; with means for normally holding the valve closed.

6. The combination in a flow retarding device of a casing having an inlet and an outlet; a valve seat in the casing having passages 50 respectively communicating with the inlet and outlet and formed with a concave face on which said passages open; a valve having a convex portion coacting with said seat and provided with a passage of less area than the inlet passage for connecting the same with the interior of the casing; a diaphragm structure supporting the valve; and means for supplying fluid under pressure to one side of said diaphragm structure.

7. The combination in a flow retarding device of a casing having an opening; a diaphragm closing the opening and provided with a passage therethrough; a ring having

55 a waste outlet and confining the diaphragm

in place; a second diaphragm engaging the ring; a hollow cap confining the second diaphragm to the ring and having its interior connected to a source of liquid under pressure; a valve carried by said two diaphragms and provided with a passage leading from its face into the casing; and a seat in the casing having inlet and outlet passage opening on its face in such position that the inlet passage is in communication with the opening in the valve when the latter is closed.

8. The combination with an alarm valve having a casing, and a main valve therein, of a flow retarding device consisting of a 70 second casing; a diaphragm dividing said casing into chambers; an outlet conduit from one of the chambers; an alarm device connected to be actuated by fluid from said conduit; a second conduit connecting the second chamber with that part of the alarm valve casing on the supply side of the valve therein; a third conduit connecting the part of the alarm valve casing on the delivery side of the valve with the first chamber of the flow retarding casing; a valve normally held closed by fluid under pressure delivered through the second conduit and normally preventing fluid flow from the third conduit to the outlet conduit.

9. The combination in a flow retarding device of a casing having an inlet and an outlet; a diaphragm structure dividing said casing into chambers; a valve connected to said structure and normally closing the outlet, there being an opening in the valve through which one of the chambers is open to the inlet; and means for supplying fluid under pressure to the other of the chambers to hold the valve closed, there being a relatively restricted waste passage from the first chamber of a cross section permitting the building up of pressure under predetermined conditions while permitting escape of liquid therefrom.

10. The combination in a flow retarding device of a casing having an opening, an annular structure adjacent the opening, and a cap for the annular structure; diaphragms confined between the annular structure and the casing and also between said structure and the cap; a valve seat mounted in the casing and communicating with an inlet; an outlet for the casing opening on said valve seat; and a valve mounted on the diaphragms and formed to co-operate with the seat.

11. The combination in a flow retarding device of a casing having an opening; an annular structure adjacent the opening, and a cap for the annular structure; diaphragms confined between the annular structure and the casing and also between said structure and the cap; a valve seat mounted in the casing and communicating with an inlet; an

outlet for the casing opening on said valve seat; and a valve mounted on the diaphragms and formed to coöperate with the seat, said valve normally closing the opening to the outlet conduit and having a passage connecting the inlet to the interior of the casing.

12. The combination in a flow retarding device of a casing having an opening; an annular structure adjacent the opening, and a cap for the annular structure; diaphragms confined between the annular structure and the casing and also between said structure and the cap; a valve seat mounted in the casing and communicating with an inlet; an outlet for the casing opening on said valve seat; a valve mounted on the diaphragms and formed to coöperate with the seat; a connection from a sprinkler system for delivering fluid under pressure to one of the diaphragms to normally maintain the valve

in a seated position; and a vent connection for the space between the diaphragms.

13. The combination in a flow retarding device of a casing having an inlet; diaphragms in the casing; a valve seat mounted in the casing and communicating with the inlet; an outlet for the casing opening on said valve seat; a valve mounted on the diaphragms and formed to coöperate with the seat, one of the diaphragms having a passage from the interior of the casing to the space between the diaphragms; and a waste connection from said space.

In testimony whereof, I have signed my name to this specification, in the presence of two subscribing witnesses.

POWELL EVANS.
